CLAIM

The ornamental design for a decorative motor vehicle air freshener, as shown and described.

DESCRIPTION

The claimed decorative motor vehicle air freshener is used as an air freshening device to freshen the air in the interior of a motor vehicle.

FIG. 1 is a front perspective view of the decorative motor vehicle air freshener of the present invention.

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.
